INVOICE ASSEMBLY FOR SERVICE ITEMS

Glenn C. Wilson, Oak Park, Ill.

Application July 19, 1949, Serial No. 105,477

2 Claims. (Cl. 282—23)

1

My invention relates to an invoice used particularly in and for the handling and identification of garments in cleaning and dyeing plants, and to the incidental services rendered to customers. For years it has been and still is customary for the salesmen of the majority of cleaning and dyeing establishments to pick up customers' garments for servicing without giving a receipt for them. The same can be said of "Will Call" stores or branch offices of main plants. It is a speculative arrangement where the customer hopes he will get his garments back from the driver, or that the "Will Call" office clerk will recognize him when he calls for his clothes. In case of a fire, theft or accidental loss of garments, the customer has no valid claim check to present. Furthermore, there are innumerable shades of colors in garments, and often there is great confusion at the "Will Call" stores when customers endeavor to identify their own clothing by color. In many cases, the customer is asked to check over the remaining garments of similar color to see if he can find his own. Then, if it happens that someone else has received his garments, confusion follows and the customer may only get his own garments back after much delay, or receive a settlement from the company. This is a highly inefficient method, and a great amount of waste results from the same. At times, if a customer insists, he may be handed a receipt to indicate that he has left certain garments to be serviced, but such a receipt is more in the nature of a makeshift, and is not capable of functioning as an office control copy or as a medium of instructions for the cleaning plant.

In many cases, when the plant driver accepts garments, he writes the name of the customer on a string tag, rolls the garments into a bundle, ties the tag to the bundle, and states which garments are to be cleaned or pressed. When the bundle reaches the plant, the service checker writes on the cloth or paper marking tags an identifying number, which is also written on the tag the driver brought in. Minor directions are given to the plant as to services desired for the particular garments. As the services are varied, it often takes a week or more to process the entire lot. Then, after what may become a frantic and confusing search, they are assembled, placed on hangers, the tag retrieved and the charges noted thereon. This serves as a C. O. D. bill which the customer pays, but a receipt is not given to him, making the method most unbusinesslike.

Some firms use manifold record books or auto-

2

graphic register forms. Their drivers or "Will Call" office clerks do not issue a customer receipt, but when garments are received, the clerks write the name and address of the customer on a white slip of paper, briefly listing the garments and services desired. These brief memos are attached to the garments, and the plant checker translates the information to manifold books or register forms, making two or three copies. Often the checker is not able to decipher the correct spelling of the customer's name or address, and much confusion follows. The original copy serves as an office record, while the other two copies are pinned to one of the garments when all services are completed. Drivers will leave one copy with the customer, and return the other to the office with the cash collected or charges noted. The invoice or statement left with or given to the customer is not a detailed personalized invoice. Furthermore, if garments are put into paper bags, there is only one invoice which covers all garments, and such invoice is attached to one of the bags. It then devolves on the customer to guess what each bag contains, and often the covering is needlessly removed from the garments a long time before they are used. The type of invoice in question has a very limited value. At "Will Call" stores, the same procedure is followed. In preparing the above garments for plant services, some firms use a paper tag, and others an unnumbered cloth tag. Then they write on the tag the number which appears on the manifold book forms or register sheets. One tag is stapled to the written forms, and the remaining tags are pinned to the garments to be serviced. Many times transposition of numbers occurs while numbers are being copied on the marking tags from invoices, causing considerable confusion. Related garments become difficult to find, and prompt assembly is impossible, resulting in delayed deliveries, and often losing valuable customers. Some firms have pre-numbered strips of paper or cloth tags. In such cases, the number is transferred to order books or register forms. Again, transposition of numbers occurs. A few firms use marking machines which type invoice numbers and give abbreviated description of garments to be serviced. Still another system is known as the "lot" method. Under this system, different colored tags are used for each week day, but these colors have no relation whatever to the customer's receipt, office control copies, or customer invoices. Thus, great difficulty is had matching up related garments, and the only reference is a like number on invoices and tags. All

of the above-described methods are incomplete and make the processing and assembling of garments most confusing, causing delays, disputes, and last but not least, added and unnecessary expense.

In order to depart from the above practices and difficulties, my invention has for one of its objects to provide a complete invoice adapted for a well-organized procedure for accurately and speedily handling all phases of the cleaning and dyeing business relative to cleaning, pressing, repairing, moth proofing, water proofing, dyeing and other wearing apparel refurbishment services.

A further object is to provide a series of individual invoice books—which may be termed service day books—these being made up in one-time carbon snap-apart style sets of five—more or less—pages of bond paper, each of which constitutes a prenumbered and marked invoice containing detailed and essential time-saving information.

A still further object is to provide a day book of the above character whose last page is a special marking tag paper with a maximum of ten separate indestructible garment identification marking tags, plus the customer's keyed claim check, all parts of the tag page having matching pre-marked numbers.

Another object is to provide an invoice book which enables the personnel of the cleaning establishment to speedily and accurately issue customers a valid claim check, to completely book customer service orders, mark in or attach pre-marked identification tags, check type of services desired, note present condition of garments, provide detailed plant instructions, and automatically prepare separate invoices for each garment with a complete history of services and charges to facilitate the correct assembly of the garments.

A still further object is to provide a plural sheet invoice with facilities to block out, delete, or make reading of all information on each customer invoice difficult except that which pertains to the garment in question and thus permit the partial delivery of an order as soon as the work is completed and yet upon close scrutiny to determine from each invoice whether there were other garments in the order.

Another object is to provide a book of the above character which makes it possible to check reference numbers for charge accounts and facilitate home storage and garment protection by means of a personalized invoice which immediately indicates the contents of each garment bag to the customer.

A further object is to provide a stub-type delivery checking voucher for every customer invoice, as a factory identification record of the same.

In the accompanying drawing—

Fig. 1 is a perspective view of the invoice book, with its component leaves in spread relation;

Fig. 2 is a plan view of an invoice sheet designed to be retained by a branch office or pick-up driver in a modified form of invoice book;

Figs. 3 to 5 are plan views of invoice pages 2, 3, and 4 respectively of the invoice book of Figure 1;

Fig. 6 is a plan view of a tag sheet which is the last page of the invoice book of Figure 1; and

Fig. 7 is a plan view similar to Fig. 3, showing a modified invoice sheet with an integral delivery checking voucher.

Referring specifically to the drawing, the novel invoice book 10 in Figure 1 is perforated at 11 to permit its leaves to be removed as needed.

When the sheets of the book are bound, the first four are interleaved with sheets of carbon paper 12. The first sheet designated by the numeral 13 is the master copy invoice sheet on which information relating to each of the plurality of items being invoiced is placed. The printed material on the main or master sheet 13 and on the plurality of accessory or individual invoice sheets 15, 16 and 17, is identical. This reading material is essential to service invoices having multiple functions. Spaces 23, 24, and 25, are provided and consecutively numbered #1, #2, and #3 for the entry of identifying information for three garments deposited by—or picked up by a driver from—a given customer for cleaning treatment. Numerous indicia relating to kinds of repair service may be checked as specified by the customer and they will later be described in detail. The master copy sheet 13 has the usual column for entries of charges opposite each of the plurality of garments or other articles to be serviced.

The main sheet 13 is intended as the office or control copy, to be kept for the records of the service establishment.

All parts of the invoice books carry the same identification number. For example, the first sheet 13 is a detailed office control record. In a modified form there is included a sheet 14 which may be used as a branch office or store checking copy. Such a sheet, if it is used, is identical to the first or master sheet. The second, third, and fourth sheets—which may be used as—15, 16, and 17 respectively—are individual invoices for each of a plurality of items. The last sheet 21 of the book is made of special tag paper capable of being fastened to a garment and going right through the cleaning processes without injury to either garment or tags. Ten separate perforated garment marking tags and the customer's claim check 22 comprise sheet 21 of the book 10. All of the sheets, as well as each of the marking tags and the customer's claim check, carry an identical number. Thus, if the customer desires information as to the progress being made in the servicing of his garments, he need only give the key number on the claim check in order to secure authentic information about the order. Further, the numbers on customer's invoices are referred to on their monthly statements if they have charge accounts. Accurate office records are more easily kept and verified with this type of numbering system, one of the most important phases thereof being that all parts are accurately pre-numbered, eliminating chances for transposition of numbers. It is therefore easy to assemble garments in their proper relation and to attach the personalized invoices to them without delay, since they carry the same key number as the garment tag identification number. An examination of the master copy invoice sheet 13 shows that there are numerous spaces and indicia for properly recording all necessary and pertinent information relative to the cleaning of garments or possibly the rendering of other services. The reference numeral 26 is directed to a space in which the type of service to be performed on the garment is checked. Beneath spaces 23, 24, 25, and 26 are a plurality of words arranged horizontally in lines 27, 28, and 29. The lines 27, 28, and 29 are consecutively numbered 1, 2, and 3 respectively and refer to the like numbered line spaces 23, 24, and 25. Each of the words in the lines 27, 28, and 29 which are duplicated in

each of these lines refers to a state or condition which the garment is in when it is delivered to the cleaning establishment for service. For example, if one of the garments to be cleaned or serviced has a belt the word "belt" is circled in the line having a number corresponding to the line identifying that particular garment. Or, if there is a stain on one of the garments the word "stain" is circled. It is obvious therefore that the cleaning establishment can and will have a better understanding of the garment they are treating and just what must be done to put it in first class condition.

To further simplify the processing of garments and speed up the flow of work, each weekly series of books is made entirely of a different colored paper to represent each working day of the week. Thus, Monday is represented by paper colored blue, Tuesday by paper colored pink, Wednesday by paper colored orange, Thursday by paper colored yellow, Friday by paper colored green, and Saturday by white paper, if the plant operates on that day. Again, if the customer desires to check on the progress of the service to his garments, he need only give the key number and the color to advise the plant just where to check for the information desired. However, the greatest amount of time is saved in the assembly department of the plant. Thus, each day drivers or store salesmen turn in a complete invoice book except for the customer's claim check with garments to be serviced for each customer. Plant checkers and inspectors attach a pre-numbered and matching colored tag to each of the garments and remove all pages from the invoice book. The master copy sheet 13 is given to the bookkeeping department, while the individual invoices for each of the plurality of garments are placed in a special invoice holder and hung on the garment assembly line. Thus, as garments are processed, it is very easy to accurately assemble them, since the individual invoices and marking tags are of a matching color and number. This speeds the orders on their way to the customers and acts as a check on the progress of the work in the plant day by day. As each garment is completely serviced the individual invoice for that particular garment is attached to it. Should orders run behind schedule, this can be detected at once and the difficulty cleared up. Thus, should a Monday invoice of blue color appear on the assembly line for Thursday, it is a signal which immediately catches the eye of the supervisors. Also, in checking daily and weekly volume of business, it is more easily ascertained by having a distinct color for each day's business of the current week, speeding up the accepting of the work, the giving of a keyed claim check to the customers, and the classification, processing, assembling, checking and delivering of the customer's garments.

One of the most important features of the novel invoice book is the line block-out. Thus, the sheets 15, 16 and 17 are involved in this feature. To begin with, when the salesman enters the customer's order on master sheet 13, such information is immediately transferred to the remaining sheets. To illustrate, it may be assumed that the customer is sending in three different garments for services. All such information will appear on sheet 13 and sheet 14 if that sheet is used in the invoice book, that is, on the lines numbered 1, 2 and 3. As the order is booked, the block-outs or printed cross hatching automatically deletes or makes reading of all infor-

mation difficult except that relative to the particular item on that individual invoice. For example, sheet 15 has the garment entry spaces 2 and 3 and the garment condition spaces 2 and 3 cross hatched, all spaces 1 and 3 are cross hatched on sheet 16; and all spaces 1 and 2 are cross hatched on sheet 17. While sheets 13 and 14 set out a complete order of a plurality of garments as a whole unit for office and plant records, the cross hatching feature makes it possible to invoice the customer for each garment separately. Thus, as garments are serviced, each one is handled as a separate order and so assembled. This permits the immediate return of individual garments to the customer as soon as services thereon are completed. And, because of the particular cross-hatching block out it is possible to read through the cross-hatching to determine if there were other garments in the order. Thus, in addition to providing a more prompt service in this manner, the overcrowding of valuable space in the plant is eliminated; and, of course, additional sales opportunities are provided on account of partial deliveries. Furthermore, the invoice constituted as described carries a complete history of the garment involved, their condition when received, what services are ordered, what the charges are for the services, a definite key number, an individual day color, and an individual garment identifying and servicing feature, making it possible to secure all the information relative to the garment and to the order in a single book.

From time to time, customers desire some added services such as a Special or rush order, Deluxe or all hand treatment of formal gowns or delicate fabrics. Then again, it might be repairing or alterations. My invention incorporates these added service references as a part of each day book invoice. Such services are referred to in the following manner. In Line 26 of the invoices sheets, the words Special, Deluxe, and Repair appear for the purpose of noting such services. Each word is followed by the figures 1-2-3. Thus if a customer desires speeded up service, it is so indicated by circling the figure after the word Special which refers to the line number of the garment which is to receive this additional service. The same method applies to Deluxe service and Repair work. Now to further quickly identify the garment to receive such services, we use the following marking system. Red marking tags are attached to the regular marking tags if Special service is desired. Those to receive Deluxe services are so identified by purple tags. Repairs are noted by tan tags being attached in like manner. With the above check, chances for errors or misunderstandings are eliminated and plant personnel can give immediate and accurate attention to the special service orders.

Fig. 7 illustrates a modified form of the invention wherein the novel book may include a series of stubs 30 to be carried by the sheets 15, 16, and 17. The stubs have printed thereon the serial number of the invoice book and a reference to the space or line which is clear—not blocked out or cross-hatched—and bears the notation of a given garment in the order. Each stub 27 serves as a delivery checking voucher. Thus, the "Will Call" stores will detach this voucher, and as they ring up the amount of cash or charge transaction, this information will be imprinted by the register upon this delivery checking voucher and thus provide a positive check with

the cash register tape, and both of these items in turn will be checked with the master sheet (3 which is the office control copy. In other words, the transaction on the delivery checking voucher indicates if it is line 1, line 2, or line 3 of the customer invoice to which it refers. Thus, when these vouchers are checked, each line is handled as a separate transaction, yet as a whole unit as far as the master sheet or office control copy is concerned. Very often in "Will Call" stores customers forget to bring their claim check. If they do so forget they are permitted to identify themselves and their garments and sign the back of delivery checking voucher for garments received. Then if they locate the claim check later, and many do and try to claim garments again, the firm has attached to the master sheet and control copy the signed delivery checking voucher showing delivery of said garments to this particular customer. This avoids false claims. Driver or route salesmen will detach delivery checking vouchers as deliveries are made and will note upon these cash received or approved charge accounts. This information will tie up with his delivery route book, all of which he will turn in at the end of each day's business with collections and credit notations. Thus again, the main office has a positive check upon deliveries and all collections or charges which are verified by checking with the master sheet or office control copy. Plants with branches in other states will find this added feature of delivery checking voucher to be an added protection against mishandling of funds or errors in services, charges, and credits.

The novel and meritorious features of the invoice book will now be summarized. First, a single writing suffices to invoice each order of a plurality of garments instantly. Further, a keyed customer receipt speedily simplifies "Will Call" service, saving extra help. Further, a positive triple check is provided for customer and individual garment identification. "Marking in" time is greatly reduced and assures full pay loads. Complete condition history of each item is noted quickly and avoids costly arguments. Detailed "easy to follow" plant instructions speed quality production. Pre-numbering of invoices and tags eliminates transposed and unreadable numbers. Matching day colors and numbers simplifies quick garment assembly. Day color identity and matching numbers with customer's name eliminate the loss of garments. The block-out or printed cross-hatching feature speeds up the delivery of finished garments, prevents plant crowding, and still permits the cleaner and customer to know whether there was more than one garment in the order and just what is being done to the other garment. The day color feature also gives a complete eye picture of the daily flow of work, eliminating bottle necks. The customer is automatically billed with a separate invoice for each item. The billing of charge accounts is greatly simplified by just listing the customer's personalized invoice number. The detailed personalized, individual garment invoices are at-

tached to the individual garment bags, eliminating guesswork as to their contents. Accurate and complete office control records with extra copies for branches are provided. More customer contacts and sales opportunities follow as a result.

I claim:

1. A plural sheet invoice for a plurality of items including a printed form master copy sheet for recording information regarding each of a plurality of items, individual invoice sheets for each of the plurality of items, said master copy sheet constituting the front page of the plural sheet invoice and having a printed form thereon including a plurality of consecutively numbered portions, said individual invoice sheets constituting succeeding pages of said plural sheet invoice, a carbon paper sheet disposed between the master copy sheet and the first of said individual invoice sheets, individual carbon paper sheets between each of the remaining individual invoice sheets, said individual invoice sheets having a printed form thereon identical to said master copy sheet, and including the plurality of consecutively numbered portions, one of said individual invoice sheet pages having all portions other than the first consecutively numbered portion having means printed thereover eliminating ready readability of succeeding consecutively numbered portions, and each of the remaining individual invoice sheet pages having all portions other than the consecutively numbered portions corresponding to each of the other pages of the invoice sheet having means printed thereover eliminating ready readability, and one identifying number on every sheet of the plural sheet invoice.

2. A plural sheet invoice as set forth in claim 1 in which the means printed over the portions of the individual invoice sheets includes a cross hatching wherein one examining the sheet may determine whether the invoice is for one or several items.
